(**) Term: **14 Years**

(57) **CLAIM**

(21) Appl. No.: **29/112,539**

The ornamental design for a reversible wire termination
blade, as shown.

(22) Filed: **Oct. 19, 1999**

DESCRIPTION

(51) LOC (7) Cl. **08-03**

FIG. 1 perspective view of the revisible blade of the present
invention, looking toward the top and right sides;

(52) U.S. Cl. **D8/99**

FIG. 2 is an elevational view of the right side;

(58) Field of Search D8/14, 51, 98,
D8/99; D15/140; 30/90.1, 90.4, 90.6-90.9,
91.1, 91.2; 81/9.4, 9.41, 9.44; 407/35, 40,
50, 54, 109, 110, 113

FIG. 3 is an elevational view of the left side;

(56) **References Cited**

FIG. 4 is a top plan view;

U.S. PATENT DOCUMENTS

FIG. 5 is a bottom plan view;

D. 409,470 * 5/1999 Barry D8/14

FIG. 6 is an elevational view of the front-end; and,

FIG. 7 is an elevational view of the back end.
